UNITED STATES PATENT OFFICE.

CHARLES A. LITTLEFIELD, OF NEW BEDFORD, MASSACHUSETTS, ASSIGNOR
TO GEORGE OTIS DRAPER, OF HOPE DALE, MASSACHUSETTS.

ROTARY EXPLOSION-MOTOR.

No. 846,087.

Specification of Letters Patent.

Patented March 5, 1907.

Application filed October 8, 1904. Serial No. 227,628.

To all whom it may concern:

Be it known that I, CHARLES A. LITTLEFIELD, a citizen of the United States, residing at New Bedford, county of Bristol, and State 5 of Massachusetts, have invented an Improvement in Rotary Explosion-Motors, of which the following description, in connection with the accompanying drawings, is a specification, like letters on the drawings 10 representing like parts.

This invention relates to motors of the type wherein the power is furnished by the explosion of successive charges of suitable explosive material, such as a mixture of gas 15 and air; and it has for its object the production of a novel explosive-motor of the rotary class, wherein the expansive force of the explosive material is utilized in an effective and economical manner.

20 By the construction hereinafter described I am enabled to secure a continuous rotation of the driving-shaft of the motor without the interposition of connected cranks and reciprocating pistons, a uniform and high speed 25 and power being attained.

Figure 1 is a side elevation of a motor embodying one form of my invention. Fig. 2 is a top or plan view thereof. Fig. 3 is an end elevation of a partial section of the 30 rotatable impact member or turbine and its casing or cylinder. Fig. 4 is an enlarged detail, principally in section on the line 4-4, Fig. 2, of the combustion-chamber and the valve which controls the admission of the exploded 35 charge to the casing of the impact member. Fig. 5 is a detail in side elevation of the means for operating the piston of a compression-cylinder. Fig. 6 is an enlarged cross-section through the two compression-cylinders on the line 6-6, Figs. 1 and 4, the pistons being shown one in elevation and the other partly broken out. Fig. 7 is a transverse 40 sectional detail, enlarged, of the impact member and its casing, the admission-ports, and the controlling-valve and reversing device on the line 7-7, Fig. 4, looking toward the right; and Fig. 8 is a similar sectional detail 45 showing the reversing device in another position. Fig. 9 is a detail similar to Fig. 7, but 50 enlarged, to show the vent-passage, to be referred to, when the controlling-valve is in normal position.

In the present embodiment of my invention the main or driving shaft of the motor has an attached rotatable impact member provided with a series of vanes inclosed within an annular casing, the propulsive force of successive charges of compressed and ignited explosive material being caused to act upon the vanes in the manner of a jet, and thereby 55 rotate the impact member and its attached shaft. The compression is in the present case effected by the action of a piston reciprocating in a cylinder into which the fresh charge of explosive material is drawn, compressed, and introduced under compression 60 into a combustion-chamber provided with a suitable ignition device. An automatically-operated valve controls the admission of the ignited charge to the casing of the impact 65 member and also permits the fresh charge as its pressure increases to drive the burnt gases of the previously-ignited charge from the combustion-chamber against the vanes of the impact member to be finally discharged thereupon through a suitable 70 exhaust-opening in its casing. A very simple and readily-operated device is provided to reverse the direction of rotation of the impact member, and a governing device is also arranged to automatically decrease the amount 75 of the charge as the speed of the motor increases. Other novel and useful features are comprehended in the invention and will be described in detail in an appropriate part of 80 the specification.

In Figs. 1 and 2 the operating parts of the motor are shown mounted on a bed-plate 1, upon which is erected a substantially circular casing 2, having a detachable wall 3, provided with a bearing 4 for the main driving-shaft 6, the annular wall of the casing preferably having a water-jacket 7 of convenient construction. A second bearing 5 for the shaft is rigidly secured to the bed-plate. The 90 casing presents for a portion of its circumference an annular chamber, in which an impact member is adapted to rotate, said member being herein shown as a disk 9, rigidly attached to the shaft 6 and having a broad peripheral face 10 to fit fluid-tight between the front and rear walls of the casing. The face 10, Figs. 4 and 7, is shaped to present a series of elongated buckets 11, extended trans-

versely across the face, and the dividing-walls 12 serve as vanes to receive the propulsive force of the motive charge, as will be described. The shaft 6 is shown as provided with a balance wheel or pulley 6^x, and beyond the bearing 5 the shaft is enlarged and provided with a worm 13, in mesh with a worm-gear 14, (see Fig. 1,) fast on a transverse shaft 15, mounted in bearings 16. These bearings are bolted to the standards 5^x of the main shaft-bearing 5 and to girths 17, bolted to said standards and also to standards 18, erected on the bed-plate and on which are mounted the actuating-levers (to be described) for the pistons of the compression-cylinders. As shown in Fig. 2, a balance-pulley 15^x is mounted on the transverse shaft 15.

Two like compression-cylinders 19 are mounted side by side back of and adjacent the casing 2, the upper ends of the cylinders being closed by extensions 20 of a casting 21, forming a combustion or ignition chamber 22, provided with a water-jacket 23. (See Fig. 6.) Each extension 20 is fitted with a valve-casing 24, having a valve-seat 25 for a valve 26, the stem 27 thereof extending into the casing and being seated by a spring 28, as will be manifest from an inspection of Fig. 6. Inlet-ports 29 establish communication between each casing 24 and the adjacent cylinder 19 when the valve is unseated against the action of the spring, the latter when seated being flush with the lower face of the extension 20. A carbureter 30, Figs. 1 and 2, of any suitable construction and having valves 31 32 to control the admission of air and a hydrocarbon, as gasolene, respectively, is connected by branches 33 with the valve-casings 24 to conduct the explosive mixture thereto. Each cylinder is provided with a reciprocating piston 34, having a rigidly-attached piston-rod 35, slideable in a guide 36 on a brace 37, secured to and extended across the lower open end of the cylinder, as clearly shown in Fig. 6. On each outward or suction stroke of the piston the vacuum created causes the valve 26 to unseat and a charge of explosive material is admitted to the cylinder to be compressed by the opposite or inward stroke of the piston.

As shown in Fig. 6, the piston is recessed in its upper face at 38 to receive the headed stem 39 of an outlet-valve 40, movable within the chamber 22 and held seated by a spring 41 to close the outlet-passages 42. When the charge is compressed, it lifts the valve 40 and passes into the chamber 22 to be ignited therein by any suitable ignition device, such as a spark-plug 43, (see Fig. 4,) and operated as will be described.

I prefer to employ a plurality of compression-cylinders and to operate them in sequence, so that a charge is being compressed in one cylinder while a fresh charge is being

introduced into another, as a more uniform and efficient operation of the motor is thereby attained.

The casting is extended at 44 to the rear wall of the casing 2 and bolted thereto and bored to receive a long tube 45, Fig. 4, extended through the casing and its front wall 3 and having at its outer end an annular flange 46, which, with the collar 47 screwed onto its inner end, prevents longitudinal movement of the tube, while permitting angular movement thereof. The inner end of said tube opens directly into the combustion-chamber 22, while its outer end is tightly closed by a screw-plug 48, bored to receive the stem 49 of a rocking or oscillating tubular valve 50, seated within the tube 45. A wheel 51, having a cross-bar 52 secured thereto, is attached to the outer end of the valve-stem 49, and a spring 53, interposed between the wheel and the outer end of the plug 48, serves to maintain the valve at all times against the inner end of the plug.

By reference to Figs. 4 and 7 it will be seen that the tube 45 is partially seated in the upper part of the casing 2 and partly in a casting 2^x, forming the head thereof, said head in practice being bolted to the casing, said head having a continuation of the water-jacket 7. (See Fig. 7.)

The combustion-chamber 22 is inclosed at its top by a cover-plate 54, so that access may be had to the chamber when necessary, the cover-plate at the top of the chamber having an internally-threaded tubular boss 55, into which is screwed the hollow shank 56 of a valve-cylinder 57. Said cylinder has a head 58, serving as a guide for the upturned end 59 of a plunger 60, Fig. 4, which closes the bore of the shank 56. The valve-cylinder has an ear 61, on which is fulcrumed at 62 one end of a long lever 63, socketed at 64 to receive the end 59 of the plunger. At its free end, which overhangs and projects forward beyond the casing 2, the lever 63 is provided with an arm 65, held in adjusted position by a nut or bolt at 66, a link 67 depending from said arm and being jointed to a block 68, embracing the rod 52 and held fixedly thereon by a set-screw 69.

When the lever 63 is rocked on its fulcrum 62, the link 67 will oscillate the wheel 51 more or less, according to the distance of the block 68 from its center, to thereby operate the valve 50. This valve in the present instance has two elongated ports 69 70, Figs. 7 and 8, about ninety degrees apart, and the tube 45 has a single outlet-port 45^x, the tube constituting a reversing device for the motor, as will appear.

I have provided the casing 2 with induction-ports arranged to coöperate with the reversing device, so that the motive fluid may act upon one or the other of the faces of the vanes 12 of the impact member 9, said induction-

ports also being arranged and constructed to prevent closure of the exit end thereof by a vane. Herein the two induction-ports are indicated by the groups of passages 71 72, 5 Fig. 7, said passages radiating substantially from the center of rotation of the valve 50 and passing through the casing 2 to the interior thereof adjacent the periphery of the impact member 9. The passages 71 are adapted 10 when operative to cause rotation of said member from right to left viewing Fig. 7, while the passages 72 when operative cause the rotation from left to right, as will be manifest.

If each induction-port consisted of a single 15 passage, its exit end would be more or less completely closed as the outer end of a vane 12 passed it, but by making each port as a plurality of passages having their exit ends arranged in a diagonal line across the path of the vanes it will be manifest that at no time 20 can all of the exit ends be closed. The same effect is secured by making a single wide passage with its mouth or exit end extended diagonally across the path of the vanes.

25 The inlet end of the induction-ports 71 72 are so arranged that the outlet 45^x will register with one or the other, so that by giving the tube 45 a rotative movement one induction-port will be opened and the other closed, 30 and vice versa, to reverse the direction of rotation of the motor.

In Fig. 7 the outlet 45^x registers with the induction-port 72, while in Fig. 8 it registers with the port 71, the reversal being readily 35 effected by a handle 73, Fig. 3, on the flange 46, a fixed segmental plate 74 having its ends 75 shaped to serve as stops to limit the throw of the handle. The admission of the contents of chamber 22 to the casing 2 is governed 40 by the valve 50, and when the induction-port 72 is open the admission-port 70 of the valve coöperates with the outlet 45^x, as in Fig. 7. When the motor is reversed, as in Fig. 8, the admission-port 69 of the valve co- 45 operates with said outlet to govern the passage of motive fluid to the induction-port 71. When a charge of explosive gas has been compressed and introduced into the chamber 22, it is ignited, the sudden increase of pressure 50 overcomes the weight of lever 63 and the parts controlled thereby and the plunger 60 is lifted, thereby elevating the outer end of lever 63 and turning the valve 50 to full-open position, as in either Fig. 7 or 8. The 55 propulsive force of the ignited charge then acts through the induction-port of the casing 2 in the manner of a jet, and impinges upon one or more of the vanes 12, forcing the impact member 9 to rotate, successive ignited charges maintaining the rotation thereof. The decrease of pressure in the chamber 22 as the ignited charge performs its work permits the plunger 60 to descend, and the lever 63 thereupon operates to close the valve 50 60 until the next charge is ignited.

Inasmuch as the burnt gases after each charge is ignited will not be completely driven out of the chamber 22 and the tubular extension 45, it is necessary to make provision to eject them, and this is effected by leaving 70 a slight vent-passage 300 when the valve 50 returns to normal position, (see Fig. 9,) the passage being merely a minute clearance or open space between the adjacent edges of the admission-port of valve 50 and the outlet 45^x. 75 The compression of the next charge is effected against this vent; but the opening is very small, and the compressed charge drives out the burnt gases of the preceding charge before it itself is ignited. Such burnt gases are 80 driven through the induction-port against the vanes and into the buckets of the impact member and escape therefrom at the bottom of the casing through openings 76 77 in the casing and bed-plate, Figs. 3 and 1. 85

Having described the means for compressing and igniting the charges of explosive material and the means for subjecting the rotatable impact member to the propulsive action of the ignited charges, I will 90 now describe the means for effecting the reciprocation of the pistons of the compression-cylinders, having particular reference to Figs. 1, 2, and 5. The shaft 15, rotated from the main driving-shaft 6 by the worm 13 and worm-gear 14, has secured upon it a cam 80 for each compression-cylinder, and in the present case there are two of such cams set opposite each other, as shown in Fig. 5, each cam being of the tappet type and serving as 100 an actuator for one of the pistons 34. Each of the standards 18 has fulcrumed thereon at 81 a rocking actuating-lever 82, adjacent the inner side of the standard and extended forward beneath one of the compression-cylinders 19, and a link 83 is jointed at its lower end to each lever at 84, the upper end of each link being pivotally connected at 85 to ears 34^x on the lower face of the piston, with which it coöperates. Each of the levers 82 105 has an upright extension 86 above the shaft 15, as clearly shown in Fig. 5, the shaft passing beneath the levers, and a downhold 87 is pivotally mounted at 88 on the inner side of the extension and provided with a rigidly-attached rearwardly-extended handle 89. The downhold is located vertically above the actuating-cam 80 for its lever, the latter having fulcrumed upon it at 90, above its own fulcrum 81, a follower 91, which is a relatively short lever, having its upper face extended beneath the downhold 87 and with an enlargement 92 on its lower face to be engaged by the cam 80. When the downhold 110 is in its operative position, as shown herein, the follower 91 is held from movement relative to its lever 82, and consequently the lever will be elevated each time the high part of the cam engages the follower and the connected piston will be moved inward in the 115 120 125 130

compression-cylinder to compress a charge of explosive material. This compression-stroke will always terminate at the same point, as will be manifest; but it may start at different points, as will be explained hereinafter. When it is desired to throw either cylinder out of operation, the corresponding handle 89 is manually depressed, thereby swinging the downhold 87 away from the follower 91, and thereafter the follower will rock on its fulcrum 90 with relation to the lever 82, the latter remaining quiescent. Each lever 82 has a depending rigid arm 93 below its fulcrum 81, upon which arm a bell-crank 94 95 is fulcrumed at 96, (most clearly shown in Fig. 5,) the longer arm 94 projecting beneath and in the path of the corresponding actuating-cam 80. A heavy leaf-spring 97 is bent at its lower end to enter a recess 98 in the rear upright face of the arm 95 of the bell-crank, the spring being held in place by a bolt 99, screwed into the arm 95, while the free upper end of the spring bears against the back of the arm 93. The bolt 99 serves to adjust the tension of the spring, as well as to secure it in place, the spring acting to keep the arm 94 of the bell-crank in cooperation with the cam as the latter rotates. When the high part of said cam is descending, it acts through the bell-crank and the spring to depress the lever 82 and effects thereby the outward or suction stroke of the piston in the compression-cylinder, a fresh charge being drawn thereinto at such time. When the motor is running at slow speed, the spring 97 will not be flexed sufficiently to permit any rocking of the bell-crank 94 95 on its fulcrum and the full suction-stroke will be made, drawing a full charge into the cylinder. As the motor speed increases, however, it is desirable to cut off the charge, and this is effected automatically through the spring and bell-crank, because the quick action of the cam on the bell-crank will flex the spring and permit some movement of the bell-crank relatively to the actuating-lever 82. Consequently the latter in its descent comes to a stop before it reaches its normal low point, and the more rapid the speed of the motor the shorter will be the descending stroke of the lever, so that the piston starts on its compression-stroke from a point nearer the top of the cylinder. Manifestly the shorter the suction-stroke the smaller will be the charge drawn into the cylinder, the amount of the charge being thus automatically regulated in accordance with the speed of the motor. A socket 100 is formed on the side of each actuating-lever 82 to receive a starting-bar when the motor is started in order to effect compression initially by hand.

Any suitable devices for operating the spark-plugs 43 can be employed, it being understood that there will be one of such plugs for each compression-cylinder employed, and

in Fig. 1 I have shown one means for operating a plug. A fixed contact 101, in electrical communication with one side 102 of an electric circuit, is secured to the casting 21, and a movable contact 103 is electrically connected with the other side 104 of the circuit, the contact being pivotally mounted at 105 on the supporting-column 120 for the adjacent cylinder, an arm 106, secured to or forming a part of the contact 103, projecting rearwardly above a stud 107 in the top of the lever extension 86. Each time the lever rises the contact 103 will be rocked and closes the circuit through the fixed contact 101, the terminals of the spark-plug being in electrical connection with the circuit in usual manner.

It will be understood that each actuating-lever 82 will operate its own circuit-changer, and in Fig. 2 I have omitted both circuit-changers to show more clearly other and more important parts.

My invention is not restricted to the precise construction and arrangement herein shown and described, as various changes or modifications may be made by those skilled in the art without departing from the spirit and scope of my invention.

Having fully described my invention, what I claim as new, and desire to secure by Letters Patent, is—

1. In a rotary motor, an annularly-chambered casing, a rotatable member therein having peripheral and radial impact-vanes movable in the annular chamber, a tubular reversing device having a peripheral outlet, a combustion-chamber communicating with one end of said device, two induction-ports in the casing radial to said reversing device and governed by the outlet therein, to direct motive fluid against one or the other face of the impact-vanes, and an intermittently-oscillating, tubular valve mounted concentric with and within the reversing device and having two outlet-ports, one or the other operating, according to the position of the reversing device, to govern admission of motive fluid to the active induction-port.

2. In a rotary explosion-motor, a rotatable member having circularly-arranged impact-vanes, a casing within which said member rotates, said casing having an induction-port, a combustion-chamber, means to introduce thereinto charges of compressed explosive material to be ignited, an oscillating valve to govern the communication between said chamber and the port, and means to operate the valve, to permit the burnt products of combustion of a charge to pass through said port during the compression of the next charge, the valve being opened wide upon the ignition thereof, and nearly closing the port during the compression of a charge.

3. In a rotary explosion-motor, a rotatable main shaft, a compression-cylinder and its piston, a rocking lever operatively con-

nected therewith to reciprocate the same, a cam rotated by said shaft and adapted to co-operate with and rock said lever, and manually-controlled means mounted on and supported wholly by the lever to throw the cam and lever out of coöperative action.

4. In a rotary explosion-motor, a rotatable main shaft, a compression-cylinder and its piston, a rocking lever operatively connected therewith to reciprocate the same, a follower carried by and also movable relatively to said lever, and manually-controlled means to prevent relative movement of the follower and maintain it in the path of the cam, whereby the latter rocks the lever, release of the follower permitting its movement by the cam relatively to the lever.

5. In an explosion-motor, a compression-cylinder, a piston adapted to reciprocate therein, a rotating actuator, and connections between it and the piston to move the latter on the compression-stroke to a fixed point

and to vary automatically the starting-point of the stroke in accordance with the speed of the motor, said connection including a cam 25 which imparts both strokes to the piston.

6. In an explosion-motor, a compression-cylinder, a piston adapted to reciprocate therein, a rotating actuator, a rocking lever having a rigid follower, and a yielding follower, to be alternately engaged by the actuator, to rock the lever, the actuator operating through the rigid follower to impart the compression-stroke of the piston, and operating through the yielding follower to retract 30 35 the piston to a varying extent in accordance with the speed of the motor.

In testimony whereof I have signed my name to this specification in the presence of two subscribing witnesses.

CHARLES A. LITTLEFIELD.
